(No Model.)

J. L. KIRBY.
CLOTHES WRINGER.

No. 329,051.

Patented Oct. 27, 1885.

UNITED STATES PATENT OFFICE.

JAMES LEONARD KIRBY, OF BOSTON, ASSIGNOR TO THE COLBY WRINGER COMPANY OF HIGHLANDVILLE, MASSACHUSETTS.

CLOTHES-WRINGER.

SPECIFICATION forming part of Letters Patent No. 329,051, dated October 27, 1885.

Application filed July 7, 1884. Serial No. 137,001. (No model.)

To all whom it may concern:

Be it known that I, JAMES LEONARD KIRBY, of Boston, in the county of Suffolk, of the Commonwealth of Massachusetts, have invented 5 a new and useful Improvement in Clothes-Wringers; and I do hereby declare the same to be described in the following specification, and represented in the accompanying drawings, of which—

10 Figure 1 is a top view, Fig. 2 an end elevation, and Fig. 3 a transverse and median section, of a wringer containing my invention, the nature of which is defined in the claim hereinafter presented. Fig. 4 is an end view 15 of the actuator. Fig. 5 is an inner side elevation of one of the jawed levers. Fig. 6 is a longitudinal section of the wringer, taken through the axes of its squeeze-rollers.

My invention relates to the class of clothes-wringers of which that shown and described 20 in the United States Patent No. 158,369, dated January 5, 1875, is a representation.

In my present wringer I have each of the 25 two end portions A of the frame provided with a stationary extension or jaw, a, projecting down from it, as represented, and in rear of such jaw I have within and fulcrumed to the said portion A a jawed lever, B, the fulcrum being a cylindrical pivot or stud, b, extending from the part A.

Between the two end portions A is the pivoted actuator C, which is an arched shelf having projecting from each end of it a journal, c, that goes through and takes a bearing in a cylindrical hole, d, in the portion A. The journal extends a short distance beyond the portion A, a pin, e, going diametrically through the extension, and serving with the actuator to aid in holding in connection 35 the portions A A. On each of the journals c is a cam, f, to bear against the upper arm of the next adjacent jawed lever B. To keep the said lever in place on its fulcrum, there projects downward from the actuator a lip, g, and also upward from such actuator another lip, h, from which it will be seen that the actuator is furnished at each end of it with two such lips, g and h. Were it not for the said lips the lever would be liable to 45 drop off its fulcrum during the movements of

the actuator. The lips keep the lever in place and save the necessity of any other device for such purpose.

The two squeeze-rollers of the wringer are shown at D and E, the shaft i of the lower one, 55 E, being journaled in the frame portions A, and provided with a crank, F.

The journals k of the upper squeeze-roller turn in movable boxes l, placed underneath two cylindrical rubber springs, m, arranged 60 in niches n, in the said end portions, A. From each box l a spindle, o, projects upward through the spring and into the tubular shank of a screw, n', that goes through the crown of the niche and screws into and through 65 a connection-bar, G, and against a washer, p, on the top of the spring. The screws and bar serve to connect the two portions A, the screws answering also to contract the springs in order to force the upper down toward the lower of 70 the squeeze-rollers.

On turning the actuator from an upright 75 down into a horizontal position its cams will so operate the jawed levers as to force their jaws toward the stationary jaws of the two portions A.

From the above it will be seen that on the wringer being placed in the usual way upon a tub, with the upper part of such tub extending between the stationary and the movable 80 jaws, such wringer may be clamped to the tub by turning the actuator down into a horizontal position or thereabout. When the actuator is in such position, the clothes as they pass from the rollers will be received 85 upon it, and by it will be prevented from falling into the tub.

I do not claim the combination of an actuator, two sets of jawed levers, two springs, and roller-supporting levers, all arranged on a pivotal shaft and applied to two squeeze-rollers, substantially as specified and represented in the aforesaid United States Patent No. 158,369, as I have in the wringer hereinbefore described but one set of jawed levers, and with 90 them have to the actuator certain lips to hold them in place on their fulcrums; therefore 95

I claim—

The combination of the actuator having lips 100 extending both upward and downward from

it at its ends, and also having a cam to each of its journals, as described, with the end portions of the frame provided with stationary jaws and fulcra, as represented, and with 5 jawed levers supported on such fulcra and arranged in rear of the stationary jaws and between the said end portions and lips, such

jawed levers having their upper arms against the periphery of the cams, and all being substantially and to operate as set forth.

JAMES LEONARD KIRBY.
